[57] ABSTRACT

A substantially stiff thin walled plastic pipe of thermoplastic material is provided having a wall of substantially uniform thickness, the longitudinal cross section profile of the wall comprising a wave form having a ratio of pitch length to amplitude of at least 3 to 1 and

ranging to as high as 15 to 1. The wall wave form can be provided as at least one peripheral groove extending spirally along the pipe, to provide a substantially non-varying flow-section; or as succeeding annular grooves and crests, whereby the flow-section varies recurrently from a maximum to a minimum value. The pipe may be produced having an integral bell housing end portion, for joinder to a succeeding pipe length or it may be produced as a continuous length. Production of the continuous length pipe can be made on machines employing travelling mould blocks, or on rotary die types of machines.
